UNITED STATES PATENT OFFICE.

FRANK J. DECK, OF BUFFALO, NEW YORK.

DESIGN FOR A BADGE.

SPECIFICATION forming part of Design No. 31,219, dated July 18, 1899.

Application filed June 12, 1899. Serial No. 720,302. Term of patent 31 years.

To all whom it may concern:

Be it known that I, FRANK J. DECK, a citizen of the United States, residing at Buffalo, in the county of Erie and State of New York, 5 have invented and produced a new and original Design for a Badge or Similar Article, of which the following is a specification, reference being had to the accompanying drawing, forming a part thereof.

10 This design relates to the ornamentation of a badge or similar article, the same being shown in the accompanying drawing, which shows a face view of my design.

15 The leading feature of my design consists of the representation of an American buffalo or bison at bay and arranged below said buffalo a dust-pan having on its front flat side

the representation of the Western Hemisphere. Connecting said buffalo with said dust-pan and forming a support for said buffalo a ribbon is displayed.

Referring to the drawing, A represents the figure of a buffalo, B the ribbon connecting the buffalo and the dust-pan C, and on the face of the dust-pan the Western Hemisphere 25 D is shown.

What I claim is—

The design for a badge or similar article, substantially as herein shown and described.

Witness my hand this 8th day of June, 1899. 30

FRANK J. DECK.

Witnesses:

HENRY L. DECK,

WILLIAM L. PFEIFFER.
